Primary Examiner — Janice Hallmark(74) *Attorney, Agent, or Firm* — Thompson Coburn LLP;
Alan H. Norman(57) **CLAIM**

The ornamental design for a water misting fan, as shown and described.

DESCRIPTION

FIG. 1 is a first perspective view of the water misting fan showing our new design;

FIG. 2 is a second perspective view of the water misting fan;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom view thereof.

The broken lines immediately adjacent the shaded areas represent the bounds of the claimed design while all other broken lines are directed to environment; the broken lines form no part of the claimed design.
